UNITED STATES PATENT OFFICE

JOHN A. WEBER, OF PORTLAND, OREGON

LOG TURNER

Application filed December 17, 1929. Serial No. 414,782.

My device is primarily intended for use in saw mills in the turning of logs as they are delivered upon the carriage from the roll way and in the turning of the log upon the carriage as the reduction of the log proceeds from the log to lumber and in the turning of cants being sawed upon the carriage. It is also used in the removing of the cants and the uncut portion of the log from the carriage.

The device in its preferred embodiment consists of independent coacting camming elements disposed upon the roll way with means for actuating the same independently by power manipulation means that are actuated by hand or foot levers and having a cam actuated turndown arm disposed upon the carriage for turning the log or cant by power means. A jump chain is provided for imparting movement to the log or cant laterally of the carriage structure in either direction as desired. The power driven cam for imparting movement to the log has a plurality of camming surfaces disposed thereupon, the purpose of which is to increase the rapidity of the movement of the cam, as the movement progresses and at the completion of the cycle of operation of the movement of the log to have the cams disappear below the bolster of the log carriage in order that the log may rest directly upon the carriage structure and against the carriage knee.

My invention is primarily intended for use in saw mills and is especially valuable where relatively small logs are to be sawed which necessitates the rapid handling of the logs to conserve time and to increase the output of the mill.

A further object of my invention is to reduce the damage to the outer surface of the log that is commonly encountered where steam niggers and log turners are used that necessitates the use of a hook or hook point engaging the surface of the log to aid in the turning operation. Through the use of my device no damage can possibly result to the exterior, or interior, surface of the log as no point, or hooks, are used in the operation of the same.

The primary object of my invention is to increase the rapidity with which the log or

cant can be precisely placed upon the carriage and from which the same may be removed or turned during the sawing operation.

A further object of my invention consists in providing simple and efficient means for the rapid handling of the log, or of the cant, in the sawing operation.

A still further object of my invention consists in providing means for the rapid and economical handling of logs and cants and through the use of which the surface of the log or cant is conserved.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a top, plan view of my assembled device shown in place upon a log carriage and adjacent the log roll-way.

Fig. 2 is a sectional, end view of the assembled device, the same being taken on line 2—2 of Fig. 1 looking in the direction indicated.

Fig. 3 is a sectional, side view of the turn-down arm illustrating the arm as being repressed within the bolster of the carriage. The same is taken on line 3—3 of Fig. 1, looking in the direction indicated.

Fig. 4 is a sectional, end view of the carriage and illustrating the driving mechanism for the shaft and illustrating the locking pin for use in the operating of the camming mechanism for one cycle of operation; the same is taken on line 4—4 of Fig. 1, looking in the direction indicated.

Fig. 5 is a top, plan view of the mechanism illustrated in Fig. 4, the same being taken on line 5—5 of Fig. 4 looking in the direction indicated.

Fig. 6 is a fragmentary, sectional, side view of the mechanism illustrated in Fig. 5, the same being taken on line 6—6 of Fig. 5 looking in the direction indicated.

Fig. 7 is a fragmentary, end view of the mechanism illustrated in Fig. 6, the same be-

ing taken on line 7—7 of Fig. 6, looking in the direction indicated.

Fig. 8 is a diagrammatical layout of a part of the log carriage, of the knee and the cam and the turndown arm disposed upon the carriage for the ejection of the log from the carriage, and illustrating a log which has been slabbed from one side and illustrating one of the camming surfaces disposed upon the roll way being raised to receive the log when transferred thereupon.

Fig. 9 is a diagrammatical layout of the camming surface, the knee and the receiving cams and illustrating the log as having been partially transferred from the carriage to the roll way.

Fig. 10 is a diagrammatical layout of the cam, the booster, the receiving cams disposed upon the roll way and the log and illustrating the log as being transferred with its flat side down upon the carriage.

Fig. 11 is a fragmentary, sectional, end elevation of a portion of the log carriage and of the knee, and illustrating the log as having been transferred with its flat side down and as resting upon the chain for transferring the log transversely of the carriage and against the knees of the carriage.

Fig. 12 is a sectional, end view of a part of the carriage and illustrating the chain as being in position for transferring a log or cant from the log carriage to the live rolls adjacent to, and parallel with the travel of the carriage.

Fig. 13 is a sectional, end view of the rope carrying spider and clutch, the same being taken on line 13—13 of Fig. 2, looking in the direction indicated.

Like reference characters refer to like parts throughout the several views.

Reference numeral 1 designates a fabricated saw mill carriage having a power driven shaft 2 running longitudinally thereof. The shaft 2 is driven by any suitable power means, as by a counter shaft 3, that leads to a source of power not here shown. A gear 4 is disposed upon shaft 2 and a gear 5 is disposed upon shaft 3 and coacts with gear 4, for transmitting the power from shaft 3 to shaft 2. A driving sprocket 7 is secured upon the shaft 2, a counter shaft 8 is journaled in spaced relationship with the driving sprocket 7 and has disposed thereabout a driven sprocket 9, which is in registerable alignment with a driving sprocket 7. The sprocket 9 rotates freely about the shaft. A sprocket chain 6 is disposed about the driving and the driven sprockets and transmits the power from shaft 2 to the rotatable sprocket 9.

Directly mounted upon counter shaft 8 is a cam 10 which has camming surface 18 whose contour is uneven and which is climaxed by a sharp surfaced point 23.

Referring to Fig. 5, a yoke 44B is jour-

naled about the shaft 8 on its one end and is supported by bracket 12A which is a part of the main frame 12 on its other end. A bearing 43B is disposed within the collar of the yoke and a lug 44A is made integral with one edge of the collar of the yoke. A locking pin 42 is slidably disposed and outwardly extends from the bearing 43B. A lever 43 is pivotally secured to lug 44A by pin 44. The locking pin 42 is movably secured to lever 43 by pin 43A. A cable 45 is secured to the free end of lever 43. A spring 46 under tension is secured on its one end to one leg of the yoke and on its other end to the free end of lever 43 and is adapted to normally maintain the locking pin 42 in intimate contact with the outer peripheral surface of disk 9B. The disk 9B is fixedly secured to shaft 8 and has on its outer periphery an offset or shoulder 9C in which locking pin 42 normally rests. A barrel 37 is made integral with disk 9B and is also disposed about shaft 8. A recess 36 is disposed through barrel 37 and disk 9B. A slot 39A is disposed within the barrel 37 and at right angles to that part of the recess 36 which is disposed in barrel 37. A locking pin 35 is slidably disposed within recess 36 and a shaft 39 is slidably disposed within slot 39A and is secured on its one end to locking pin 35. Slot 39A is in registerable alignment with offset 9C. Since the locking pin 42 normally rests within the offset 9C the shaft 39 connected to locking pin 35 is prevented from moving forward with slot 39A. A spring 38 is disposed within recess 36 which is adapted to normally maintain the locking pin 35 under tension. A roller 40 is rotatably journaled on the free end of shaft 39 and is in registerable alignment with the edge of locking pin 42. Stop 9A is secured to that side of sprocket 9 which faces disk 9B. Locking pin 35 has an engaging end 41 that is in registerable alignment with stop 9A.

Bearing this particular structure in mind, the mechanism illustrated in Figs. 5, 6 and 7 operates in the following manner: The power of shaft 3 is transmitted to shaft 2 which in turn transmits power to sprocket 9 that turns freely about shaft 8. When it is desired to place the cam 10 and its allied structure in operation, cable 45 is pulled which releases locking pin 42 from the offset 9C disposed on the peripheral edge of disk 9B, and permits shaft 39 to slide forward due to the spring 38 and locking pin 35 is pushed forward and catches on stop 9A disposed on the sprocket 9 which is continuously rotating. This makes a driving locking engagement between the disk mechanism and the sprocket 9 and since the disk 9B and also the cam 10 are securely attached to shaft 8 they will rotate in the same direction that sprocket 9 rotates. The tension on the cable 45 is released immediately after the locking pin 42 is disengaged from the offset 9C and such re-

lease permits lever 43 to be tensioned by spring 46. This places locking pin 42 again on the outer periphery of the disk 9B. When the disk 9B has completed one revolution the roller 40 comes in contact with the sloping surface 47 of the locking pin 42 and gives way laterally a sufficient distance to disengage the end 41 of locking pin 35 from stop 9A and the locking pin 42 engages the offset 9C preventing backward rotation of the disk 9B and maintaining locking pin 35 out of engagement with stop 9A.

An arm 11 is hingedly journaled about journal pin 15 that is secured to frame 12. The frame 12 is horizontally disposed and fixedly positioned upon the saw mill carriage 1.

A camming arm 16 is also hingedly journaled to the frame 12 but is adapted to swing in the opposite direction from the cam arm 11. It is positioned in a different horizontal plane from, and is adapted to rest upon cam arm 11. Cam arm 16 has an even upper surface and an uneven lower surface with a very pronounced projecting surface at 22. Cam arm 11 has a substantially even upper surface but has a cut out portion 21A shaped to fit the contour of the projecting surface 22 near its free end. The tip 21 of the cam arm 11 is hook-shaped. Cam roller 13 is journaled about journal pin 14 which is secured to the arm 11 and which rests upon the camming surface disposed upon cam arm 11. The normal inoperative position of the cam and camming arms is shown in Figs. 1, 3 and 8, where in the cam roller 13 is resting within the socket 18A of the camming surface 18 and camming arms 11 and 16 are in substantially horizontal position and resting upon each other.

The operation of the cam and camming arms may be easily followed in Fig. 8, which shows number 1 position, Fig. 9 which shows position number 2, Fig. 10 which shows position number 3, Fig. 11 which shows position number 4. Referring to Fig. 8 the log 19 shown resting against knee 20 disposed on carriage 1 is shown as having been partly cut and ready to be turned for another cutting. The application of tension upon cable 45 connects sprocket 9 with disk 9A which causes cam 10 to rotate in the direction of the arrows, and as the cam is rotated, the cam roller riding upon the camming surface 18 lifts cam arm 11, which in turn lifts cam arm 16, as shown in Fig. 9. When the cam roller is about to reach the sharp surface point 23, the tip 21 of cam arm 11 is positioned upon the projecting surface 22 of cam arm 16 and when the roller reaches the sharp surfaced point 23, a shock is imparted to cam 11 which in turn shocks cam arm 16 and which kicks the log 19 off balance and positively insures the turning of the log upon its cut surface. By this time the cam 10 has completed its

cycle of rotation as the locking pin 35 has been disengaged from stop 9A and the cam mechanism is again in a normal position, as shown in Fig. 10, with the log turned. In order to break the drop which the cam arm 11 takes when it leaves point 23, resilient support 24 is secured to the carriage frame in direct alignment with the tip 21 of the camming arm 11 and as the arm drops, the tip 21 falls upon the resilient support 24 which prevents undue strain upon the arm 11.

To assist the log turning cam 10 and cam arms 11 and 16 and to prevent the over turning of the log upon the roll way, a cam 25 is rockably secured to a pin 26 journaled within the roll way 27. A line 28 passes about the hub 29 of the cam and as the line 28 is operated by manual means, or otherwise, it rotates in the direction of the arrows and the cam 25 is raised from its normal position as illustrated in Figs. 2 and 11, in order that the flat side of the log that has been turned might fall upon the cam as illustrated in Fig. 9. To positively prevent the over turning of the log 19, I provide a second cam 30 that is also rockably disposed about a pin 31 secured to the roll way 27. A line 32 passes about a hub 32A of the cam and as the line is operated the cam 30 is raised and rotates in the same direction as the arrows shown. The cam 30 is substantially larger in diameter than the cam 25 and when raised into position as illustrated in Fig. 9 is adapted to receive log 19 if it rolled over too much and thus prevents the over turning of the log upon the roll way. Each of the cams 25 and 30 are independently actuated in either direction by manipulating lines 28 and 32.

After the log has been brought into the position as illustrated in Fig. 10 the cam arms 11 and 16 have returned to their normal positions and the log then rests partly upon the cams 25 and 30 and partly upon the carriage itself.

Referring to Fig. 2, a journal bearing 49A having stepped cam faces is secured to the carriage. A shaft 48 is loosely journaled within the bearing. A hub 49 having stepped cam faces adapted to fit the faces on the bearing is rotatably disposed upon the shaft and is maintained in intimate contact with the cam faces of bearing 49A by a collar 48A fixedly disposed about the shaft. A plurality of arms 50 are made integral with the hub as illustrated in detail in Fig. 13. A groove 51 is disposed at the end of the arms and a cord 52 is disposed therein. A head 54 having a pair of slots 55 is disposed at an angle and in spaced relation to permit vertico-lateral movement of the head in relation to the carriage. Pins 56 are secured to the saw mill carriage and the clots in the head are slidably disposed about the pins. A link 53 is disposed between the head 54 and the shaft 48. When the cord 52 is pulled, the

stepped cam faces upon the bearing 49A and the hub 49 are placed out of alignment as the relationship of the faces is changed and consequently a forward movement is imparted to the shaft and link since the hub is rotatably disposed upon the shaft. This forward movement forces the head 54 to slide upon the pins 56 on its slots and raises the head sufficiently to contact with the log 19 which has been placed in the position shown in Fig. 10 by the action of the cam 10 and also cams 25 and 30. The forward movement of the shaft 48 and link 53 is not great but sufficient to impart vertical-lateral movement to the head. There is sufficient play within the journal bearing 49A to permit such movement as is here contemplated. A sprocket 58 is secured about shaft 2 and is in registerable alignment with the head 54. A sprocket 26 chain 57 is disposed about the head 54 and the sprocket 58 and imparts continuous rotation to the head sprocket, not shown. The raising of the head 54 as above outlined places the chain 57 into contact with the under surface of the log 19 and this moves the log laterally toward the knees of the carriage as illustrated in Fig. 11.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:—

1. In a device of the class described, in combination with a saw mill carriage and a roll way, a shaft mounted upon the carriage, a continuous running sprocket mounted upon the shaft and normally free to rotate thereupon, a cam fixedly mounted upon the shaft, camming turndown arms disposed in registerable alignment with the cam mounted upon the shaft, locking means fixedly disposed about the shaft, hand manipulative means for engaging the locking means with the sprocket and subsequently disengaging said means to cause a rotation of the cam through a single cycle of operation and for normally raising the camming turndown arms, hand manipulative cams rockably disposed upon the roll way and in registerable alignment with the log disposed upon the carriage adapted to receive the log when partially rotated by the cam arms, and power driven hand manipulative means for imparting a lateral movement of the log relative to the carriage and the roll way to position the log in its partially rotated position against the knees.

2. In a device of the class described, in combination with a saw mill carriage and a roll way, a plurality of turndown cam arms

hingedly secured to and in line with the deck of the carriage, and superimposed one above the other, a cam disposed in registerable alignment with the cam arms and adapted to raise the cam arms, means for rotating the cam for one cycle of operation in order to manipulate the turndown cam arms, hand manipulative cams rockably secured to the roll way and in registerable alignment with the log disposed upon the carriage and adapted to receive the log when partially rotated by the cam arms, a plurality of transfer chains disposed transversely of the carriage, and means for manipulating the transfer chains into contact with the under side of a log for moving the log laterally relative to the carriage and the roll way in order to position the log against the knees of the carriage.

3. In a device of the class described, in combination with a saw mill carriage and a roll way, a shaft journaled within the carriage, a sprocket rotatably disposed about the shaft and free to rotate thereon, hand manipulative means disposed about the shaft for locking the sprocket to the shaft, means for maintaining the sprocket in locked position for one cycle of operation, a cam fixedly disposed about the shaft, turndown cam arms superimposed one upon the other hingedly disposed in registerable alignment with the cam at the side of the carriage, said arms being adapted for actuation by the cam, a pair of cams rockably journaled to the roll way and adapted to receive the log when turned by the cam arms, and means for moving the log laterally of the carriage and against the knees when the log has been rotated by the turndown cams.

4. In a device of the class described, in combination with a saw mill carriage, a pair of turndown cam arms hingedly disposed centrally and transversely of the carriage, one of said arms resting upon the other and adapted to swing in the opposite direction, said cam arms normally lying below the deck of the carriage, a shaft journaled within the carriage, a cam fixedly disposed about the shaft and in registerable alignment with the cam arms, a freely running sprocket disposed upon the shaft in spaced relation with the cam, and means fixedly disposed upon the shaft and between the sprocket and the cam for locking the sprocket to the shaft.

5. In a device of the class described, in combination with a saw mill carriage, a pair of turndown cam arms hingedly disposed centrally and transversely of the carriage, one of said arms resting upon the other and adapted to swing in the opposite direction, said cams normally lying below the deck of the carriage, a shaft journaled within the carriage, a cam fixedly disposed about the shaft and in registerable alignment with the cam arms, a freely rotatable sprocket disposed upon the shaft in spaced relation with

the cam, means fixedly disposed upon the shaft and between the sprocket and the cam for locking the sprocket to the shaft assembly, and automatic means for releasing the locking means after one cycle of rotation of the cam.

6. In a device of the class described, in combination with a saw mill carriage, a driving shaft journaled within the carriage, a counter shaft parallelly disposed within the carriage in spaced relationship with the driving shaft, a driving element fixedly disposed about the driving shaft, a driven element rotatably disposed about the counter shaft, 10 a yoke fixedly disposed about same shaft, a cam disposed about the counter shaft, hinged means disposed at the side of the carriage and superimposed one above the other and adapted for being actuated by the cam, means 15 disposed upon the counter shaft for engaging the side of the driven element freely disposed upon the shaft, and thereby rotate the counter shaft, and means associated with the locking means for automatically releasing 20 the driven element from engagement with the locking means after one cycle of operation of the cam.

7. In a device of the class described, in combination, a saw mill carriage, a pair of 30 turndown cam arms superimposed one above the other and hingedly disposed to swing in opposite directions and normally lying below the surface of the carriage, a shaft journaled within the carriage, a freely rotatable element disposed about the shaft, a cam fixedly disposed about the shaft, means fixedly disposed upon the shaft for transmitting power from the freely rotatable element to the shaft, manually operable means 35 for placing in operation the first mentioned means, automatic means for breaking the revolution of the combined mechanism after the cam completes one cycle of rotation, which raises the turndown cam arms and 40 45 rolls the log over, a roll way disposed in spaced relation from the carriage, cams rockably secured thereto, said cams in registerable alignment with the log disposed upon the carriage, and adapted to receive the log 50 when being rotated by the cam arms, manually operable means for manipulating the cams, a plurality of transfer chains disposed transversely of the carriage and in spaced relation to each other, and manually operable 55 means for placing the chains above the surface of the carriage in order to move the log from the cams and laterally of the carriage to the knees.

JOHN A. WEBER.
